UNITED STATES PATENT OFFICE

LISTON B. WILSON AND ISAAC A. WILSON, OF ZANESVILLE, OHIO.

CHURN.

SPECIFICATION forming part of Letters Patent No. 237,792, dated February 15, 1881.

Application filed November 26, 1880. (No model.)

To all whom it may concern:

Be it known that we, LISTON B. WILSON and ISAAC A. WILSON, of Zanesville, in the county of Muskingum and State of Ohio, have jointly 5 invented certain new and useful Improvements in Churns; and we do hereby declare the following to be a full, clear, and exact description of the invention, such as will enable others skilled in the art to which it pertains to make 10 and use it, reference being had to the accompanying drawings, which form part of this specification.

Our invention relates to an improvement in reciprocating churning, and is designed to provide 15 a churn of simple construction and of easy operation, speedily bringing about the desired result, and one that may be manufactured and supplied to the trade at a comparatively light cost.

With these ends in view our invention consists in a churn-dasher consisting, essentially, 20 of two body-pieces framed together at right angles, the dash-rod being joined therewith at the point of intersection; of two different-sized rectangular structures attached to the lower 25 face of the framed body-pieces, and a single rectangular structure attached to the upper face of the body-pieces, said upper structure being intermediate in size and located directly 30 over the space between the two structures on the lower face of the dasher.

In the accompanying drawings, Figure 1 is a front elevation of our improved churn as constructed in accordance with our invention. 35 Fig. 2 is a plan view of the churn-dasher. Fig. 3 is a plan view of the under side thereof, and Fig. 4 is a view in end elevation.

Let A represent the churn-standard; B, inclined beams supporting upright posts C.

D are cross-pieces secured to the upper ends 40 of the upright posts C, and E is a horizontal beam attached to the outer ends of the cross-pieces D, said cross-pieces D and beam E forming a frame to support the dash-rod F'. The beam E is provided at F³ with a circular recess, 45 in which the dash-rod is received and has vertical movement.

Fly-wheel G is mounted on shaft A', journaled in boxes B' secured to the cross-beams C' C², which latter are secured at each end to the upright posts C C.

The rear end of shaft A', which projects through the journal-box B', is provided with a pinion, D', which meshes with an internally-toothed spur-gear wheel, D², pivotally secured 55 to the rear cross-beam, C², and actuated in rotation by handle D³. The advantage of using the internally-toothed spur-gear and pinion lies in the fact that with the same strength of tooth the gears are capable of transmitting 60 greater force, as a greater number of teeth are at the same time in engagement.

The front end of the shaft A', which projects through journal-box B' mounted on cross-beam C', is provided with a governor, D⁴, having one 65 end, E', weighted with a ball, E², and the other end, E³, provided with a number of apertures, a, into which the lower end of the pitman-rod E⁵ is adapted to be received in adjustable engagement. The upper end of the dasher-rod 70 F' is also provided with a number of apertures, a', into which the upper end of the pitman E⁵ is received. The object of thus providing several different adjustments for the pitman-rod is to enable the plunge of the dash to be regulated according to the amount of cream to be 75 churned, allowing the same churning-vessel to be used, even though the amount of cream to be churned is very small. While in use the dash-rod is retained within the circular recess 80 F³ in the dash-support E by a latch, b', swinging on a pivot or screw, b². When it is desired to remove the dasher from the churn it may be easily done by lifting the latch and removing the lid G' of the churn G³, which latter 85 may be of any approved form of construction.

The dasher shown in Figs. 2 and 3 of the drawings consists of two body or frame pieces, c c, framed together at right angles. On the lower face of these cross-pieces two rectangular structures are formed, each consisting of four pieces of wood, c' c' c' c' d' d' d' d'; or they may, if found expedient, be formed of a single piece of material.

The upper face of the frame structure is provided with a rectangular structure formed of the pieces b' b' b' b' intermediate in size between the two structures on the under face of the dasher and directly over the aperture formed between them. The action of the whole structure forming the dasher, presenting many angles, as it does, will be to lash the cream vio-

lently and separate the butter globules in the cream from the milk in a short time. The fly-wheel and governor impart a steady and even action to the churning motion, completely overcoming the shock of the dasher as it strikes a broad surface of heavy cream, and which is so objectionable to the operator and wearing to the churn in the old constructions. Having fully described our invention, what we claim as new, and desire to secure by Letters Patent, is—

A churn-dasher consisting, essentially, of two body-pieces framed together at right angles, the dash-rod being joined therewith at the point of intersection, of two different-sized rectangular structures attached to the lower

face of the framed body-pieces, and a single rectangular structure attached to the upper face of the body-pieces, said upper structure being intermediate in size and located directly over the space between the two structures on the lower face of the dasher, substantially as set forth.

In testimony that we claim the foregoing we have hereunto set our hands this 8th day of November, 1880.
